UNITED STATES PATENT OFFICE.

EMIL BENTE, OF BARMEN, GERMANY, ASSIGNOR TO MAX HENKELS, OF NEW YORK, N. Y.

MACHINE-BRAIDED LACE.

Application filed October 22, 1924. Serial No. 745,098.

To all whom it may concern:

Be it known that I, EMIL BENTE, a citizen of the German Empire, and residing at Barmen, Rhenish Prussia, Germany, have 5 invented certain new and useful Improvements in Machine-Braided Lace, of which the following is a specification.

My invention relates to a machine-braided lace the ground-work of which consists of 10 a net of square meshes and of a net of rhombic meshes, the latter being arranged either within the square meshes or in staggered relation thereto. Laces of this kind are well known per se.

One object of my present invention is to 15 produce a lace of the kind above referred to which is distinguished from the known lace by its high degree of clearness and delicacy. Another object is to produce a 20 firm and durable lace structure with a comparatively small number of threads.

With these and other objects in view, my 25 invention consists of a novel arrangement and combination of threads fully described in the following description, reference being 30 made to the annexed drawing which shows, by way of example, two preferred embodiments of my new lace.

In the drawings: 35 Fig. 1 is a piece of lace of about actual size.

Fig. 2 is a part of this lace drawn on an enlarged scale.

Fig. 3 is a second piece of lace of about 40 actual size, and

Fig. 4 is again a part of this lace drawn on an enlarged scale.

Referring first to Figs. 1 and 2, the 45 ground-work of the lace comprises a series of spaced single threads *a* running like warp threads straight through in the longitudinal direction of the lace, and pairs of strips *b*, *c* arranged in the spaces between the said single threads *a*, each strip consisting of 50 two entwisted threads. The single threads *a* are, preferably, more heavily tensioned than the threads of the strips *b*, *c*. At certain, regular intervals the strips *b*, *c* are connected alternately with another and 55 simultaneously with single threads *a* at

d, *d*, and, in the spaces between the threads *a*, *a*, merely with another at *f*, *f*, the connections being effected, in the first instance, by braiding the four threads of two adjacent 60 strips and the single thread lying between them together, in the second instance, by

interbraiding the four threads of the two strips which meet each other at the connecting places *f*, *f*. Thus the strips *b*, *c* are drawn into a zig-zag course whereby substantially rhombic meshes are formed. 65

As is evident from the drawing, the connecting places *d*, *d* and *f*, *f* are each arranged in transverse rows as well as in longitudinal rows. Regarding now the longitudinal 70 direction of the lace which direction is indicated by the arrow *x*, at each alternate transverse row of connections, namely at the places *d*, *d*, transverse spokes interconnecting said places are formed in the following manner. One thread of the four threads of the two strips engaged in a connecting place *d*, for example, in the one row a thread *b*¹, and in the next right adjacent row a thread *c*¹, is transferred, in a weft-like manner, from one connecting place *d* to a transversely adjacent place *d*, the thread leaving such a place on one side of the latter being each time replaced by another thread entering said place on the opposite side. These weft-like threads or spokes *b*¹, *c*¹ form together with the longitudinal threads *a*, *a* square meshes which are in the longitudinal direction as well as in the transverse direction of the lace displaced with 75 respect to the rhombic meshes formed by the strips *b*, *c*, or, in other words, are so staggered to the latter meshes that the ground-work of the lace appears to be composed of 80 square meshes the corners of which are connected by diagonally arranged crosses. 85

As is evident from the drawing, the lace ground produced by the above-described arrangement and combination of threads is 90 a peculiar clear, fine and delicate one. It contains only a comparatively small number of threads, but, nevertheless, the structure of the lace is exceedingly firm and durable, because, on the one hand, two of the corners of the rhombic meshes are connected by thread forming the edges of the 95 square meshes, while, on the other hand, the corners of these meshes are in their turn connected by the strips *b*, *b*. Thus distortion of the lace is entirely impossible. 100

Of course, any known figure-work or pattern may be applied to the new ground-work of the lace. I have omitted the patterns from the drawing, because they do 105 not form part of the invention.

Referring now to Figs. 3 and 4, the lace

shown therein substantially corresponds to the example illustrated in Figs. 1 and 2 in the number as well as in the arrangement of the single threads a , a and of the strips b , c .
5 The main difference lies in this that the spokes which form the transverse edges or sides of the square meshes, are no more situated at the connecting places d , d of the strips b , c and the single threads a , a , but at 10 the other connecting places f , f . To this end, the latter connections are somewhat reinforced by a more frequent interbraiding of the four threads of the two strips meeting each other at these places, while the trans- 15 verse or weft-like spokes are formed, in a manner similar to that described with reference to Figs. 1 and 2, by transferring the threads b^1 and c^1 , respectively, from one connecting or braided place f to the adjacent place f . The character of the ground-work produced in this way differs from that shown in Figs. 1 and 2 only in that the square meshes coincide with a part of the 20 rhombic meshes so that in each square mesh 25 a rhombic mesh is arranged. The ground-work of the lace illustrated in Figs. 3 and 4 is of the same clearness and delicacy as the ground-work according to Figs. 1 and 2, and its structure possesses also the same degree 30 of firmness and tenacity or durability.

I wish it to be stated that my invention is not restricted to the precise embodiments shown, on the contrary, many alterations and variations may suggest themselves to 35 those skilled in the art without departing from the scope of my invention as pointed out in the claims.

Having now fully described my invention, what I claim is:

40 1. In a machine-braided lace, a ground comprising a plurality of parallelly spaced, relatively heavily tensioned single threads running in warp-like manner the length of the lace, designed to form the longitudinal 45 sides of the ground meshes, a plurality of lighter tensioned zigzag strips intercross-

ingly running obliquely across between the said single threads and each strip consisting of two entwisted threads, said strips being interbraided at alternate points with one another and one of said single threads, and intermediate two such single threads with one another only, and weft-like transverse spokes of a single thread each, designed to form the transverse sides of the ground meshes, and each spoke connecting two transversely adjacent connecting points in each second transverse row thereof, each spoke being formed by one thread of one of said diagonal strips being transferred at 50 a sharp angle at the respective connecting point across to the next respectively transversely adjacent connecting point.

2. In a machine-braided lace, a ground comprising a plurality of parallelly spaced, 55 relatively heavily tensioned single threads running in warp-like manner the length of the lace and forming the longitudinal sides of the rectangular ground meshes, a plurality of lighter tensioned zigzag strips intercrossingly running obliquely across between the said single threads and each strip consisting of two entwisted threads, said strips being interbraided at alternate points with one another and one of said single threads, and intermediate each two such single threads with one another only, and weft-like transverse spokes of a single thread each forming the transverse sides of the ground meshes and always connecting two 60 transversely adjacent points where two strips and the longitudinal single threads meet, each spoke formed by one thread of one of said diagonal strips being transferred at 65 a sharp angle at the respective connecting point across the space between two longitudinal single threads to the next respectively transversely adjacent connecting point.

In testimony whereof I affix my signature.

EMIL BENTE.
